UNITED STATES PATENT OFFICE

GEORGE F. HANDLEY, OF GLENDALE, NEW YORK, ASSIGNOR TO ROYAL TYPEWRITER COMPANY, INC., OF NEW YORK, N. Y., A CORPORATION OF NEW YORK

TYPEWRITING MACHINE

Application filed December 11, 1928. Serial No. 325,320.

This invention relates generally to improvements in typewriting machines, but more specifically to a billing device employed in connection with and forming a part of a typewriting machine.

In billing operations generally, it is desirable to typewrite individual invoices and simultaneously record the typewritten data on a sales journal or book sheet. The book sheet is first placed around the platen and then the first invoice and intermediate carbon are placed around the platen in front of the book sheet. The account data is then printed simultaneously on the invoice and on the book sheet, and the invoice and carbon are then removed from the machine. The operator then effects a line spacing operation to the book sheet, another invoice and carbon are then inserted, and the new data is then printed simultaneously on the invoice and book sheet. Heretofore it has been usual to turn the platen backwardly, together with the record sheet and carbon to receive the new invoice, and then to turn the platen forwardly into its position for writing the first line upon the invoice.

The principal object of the present invention is to provide means including a manually operable lever which during movement of the lever will successively effect a line spacing operation and a release of said pressure rolls whereby the book sheet will be line spaced and the pressure rolls will be immediately thereafter released to permit the ready withdrawal of the printed invoice and carbon and the ready insertion of a new invoice and carbon, the return movement of the operating lever effecting the return of the pressure rolls to operative position, without however effecting the line spacing mechanism.

A further object of the invention lies in the provision of a second manually operable lever for releasing the pressure rolls only and movable entirely independent of the lever which effects the successive line spacing operation and the release of the pressure rolls, thus permitting the invoice to be adjusted properly with respect to the book sheet.

In the accompanying drawings:

Figure 1 is a front elevation of a typewriter carriage embodying the subject matter of my invention,

Figure 2 is an end elevation thereof, the parts being in normal position,

Figure 3 is a similar view, but showing the platen at the end of a line spacing movement and also showing the pressure rolls released from the platen,

Figure 4 is a detail sectional view showing the means for supporting the pressure rolls,

Figure 5 is a detail elevation showing adjustable means for varying the line spacing movement of the platen,

Figure 6 is a perspective view of the arm which supports the line spacing pawl,

Figure 7 is a perspective view of the latch associated with the line spacing mechanism,

Figure 8 is a perspective view of the lever for effecting in succession the line spacing operation and the release of the pressure rolls,

Figure 9 is a detail elevation showing the second manually operable lever and its relation to the means for releasing the pressure rolls, and

Figure 10 is an elevation of a pinion.

In the accompanying drawings, there is illustrated a portion of a Royal typewriting machine, although if any other typewriter may be employed if desired.

The machine includes a carriage A having end plates 5 and a platen B having axles 6 which are respectively journaled in said end plates. The carriage includes on its left side the usual line spacing means (not shown) which is employed where the usual single line spacing is required between separate items on invoices. Such line spacing means may be constructed in accordance with the Hess & Myers Patent 1,427,468, Aug. 29, 1922.

Front pressure rolls 7, which are in the form of sleeves, are loosely fitted on a rod 8 extending parallel with the platen. Obviously one or more rolls 7 may be employed as desired. The rod 8 is supported on the forwardly extending arms 9 of bell crank levers 10 which are pivoted at their angles as at 11 to the carriage A. The rearwardly extending arms 12 respectively engage in

cam grooves 13 which extend transversely of an oscillating or rock shaft 14 and bear against the respective bottom or eccentric surfaces 15 formed by said grooves, as shown in Figure 4. Coil springs 16 are each connected at one end as at 17 to the forwardly extending arm 9 of the bell crank lever 10, and at its other end to a pin 18 fixed to the carriage A. These springs function to normally and yieldably retain the front pressure roll 7 in contact with the platen. Upon oscillation of the rock shaft 14 in one direction, the cam surfaces 15 will oscillate the bell crank levers 10 against the tension of the springs 16 and thereby release or separate the front pressure rolls from the platen.

A rear pressure roll 19 has its ends journaled in lever arms 20, one only being shown, which have their rear ends pivoted as at 21 to the carriage A. The free ends of the arms 20 are each engaged in a cam groove which extends transversely of the rock shaft 14, and bears against the bottom or eccentric surface 22 formed by said groove, as shown in Figure 4. A flat spring 23 is connected at one end to the carriage A and has its free end bearing on the arm 20 to normally and yieldably retain the rear pressure roll 19 in contact with the platen. On oscillation of the rock shaft 14 in one direction, the cam surfaces 22 will swing the lever arm 20 against the tension of the spring 23 and thereby release or separate the rear pressure roll from the platen.

In order to actuate the rock shaft 14, I have pivoted a manually operable lever 24 on a stud screw 25 mounted on the right hand end plate 5 of the carriage. This lever is provided with an arcuate rack 26 which engages a gear 27 fixed to the rock shaft 14. Thus upon a forward pull on the lever 24 by the operator, the rock shaft 14 will be oscillated in a direction to release simultaneously the pressure rolls 7 and 19 from contact with the platen, and upon release of said lever by the operator, the springs 16 and 23 will automatically return all of the parts to their initial positions.

In order to effect a line spacing operation of the platen and simultaneously release the pressure rolls 7 and 19 from contact with the platen, I have provided the following mechanism:

The axle 6 on the right hand end of the carriage, projects beyond the end plate 5 and a bracket 28 is loosely mounted on the projecting portion of the axle 6. This bracket includes a plate 29 and upper and lower plates 30 and 31 respectively, the plates 30 and 31 being disposed in the same vertical plane and being united with the plate 29 through the medium of a connecting portion 32, the bracket 28 being held against rotary movement when the platen is turned, by means of a rod 33 which connects the end plate 5 and the plate

29 of said bracket. A combined line spacing and pressure roll releasing lever 34 is pivotally mounted on the axle 6 adjacent the plates 30 and 31 of the bracket 28. Also journaled on the axle 6 is a pawl or supporting arm 35, and to the outer end of this arm is pivotally connected as at 36 one end of a pawl 37 adapted to engage a ratchet wheel 38 fixed to the axle 6 of the platen. A coil spring 39 has one end connected to the pawl 37 and the other end connected to the arm 35 for yieldably urging the pawl into engagement with the ratchet wheel 38. A stop, 40, as shown in Figures 1 and 5, extends laterally from the front edge of the plate 29 of the bracket 28 and serves to limit the downward movement of the arm 35. A latch 41 is pivotally connected intermediate its ends as at 42 to the lever 34. One end of the latch 41 is provided in its under surface with a cutout 43 forming a resultant shoulder 44. The cutout 43 is normally adapted to embrace a pin 45 which is angular in cross-section and extends laterally from the pawl supporting arm 35, the shoulder 44 co-operating with the pin to normally connect the arm 35 with the lever 34. A coil spring 46 is connected at one end to a pin 47 fixed to the lever 34 and at its other end to a pin 48 fixed to the end of the latch 41 at a point adjacent the shoulder 44. This spring 46 functions to yieldably retain the latch in engagement with the pin 45. It will be observed that as long as the latch 41 is connected with the pin 45, the pawl 37 will be moved rearwardly with the lever 34 in order to bring about a line spacing operation to the platen. After the platen has been rotated a predetermined distance so as to effect a line spacing movement, it is desirable to disconnect the latch from the line spacing mechanism so as to permit the lever 34 during its continued movement in the same direction to effect a release of the pressure rolls 7 and 19. To this end, I have provided the plate 30 of the bracket 28 with a pin 49 against which the nose 50 of the pawl 41 will engage and thereby swing said pawl upon its pivot 42 and release the shoulder 44 from the pin 45, thereby disconnecting said latch from the line spacing means.

It is desirable to provide means for varying the extent of movement imparted to the platen during the line spacing operation so as to permit one or more line spacings as may be desired. For this purpose, I have provided a shield 51 for the pawl 37. This shield 51 is provided with a supporting flange 52 having an arcuate slot 53 formed therein. Screws 54 extend through the slot 53 and engage threaded openings in the plate 29 of the bracket 28. By means of this pin and slot connection between the bracket and the shield, the latter may be adjusted relative to the pawl and thereby vary the time when the pawl 37 engages the ratchet wheel 38. The earlier the pawl engages the ratchet wheel the greater

will be the line spacing movement imparted to the platen, and vice versa, the later the pawl engages the ratchet wheel the lesser the movement. The flange 52 is formed on its lower edge with a series of ratchet teeth 55 which are engageable with a retaining pawl 56 pivoted on the plate 29 as at 57 and yieldably held in engagement with the teeth by a spring 58.

In order to effect a release of the pressure rolls 7 and 19 immediately following the line spacing operation and during the latter part of the movement of the lever 34 in one direction, I have provided the lower end of said lever with an arcuate cutout 59 which is arranged concentrically with the axis of said lever, and forms resultant spaced stop shoulders 60 and 61. Fixedly connected to the gear 27 is a laterally extending arm 62, said arm extending to the right as viewed in Figure 1, and having a rigid gear 63, similar to the gear 27, fixed thereto, the gear 63 being pivotally supported on the plate 31 through the medium of the pivot pin 64. A gear 65, as shown particularly in Figure 10, is pivoted on a screw 66 carried by the plate 31 of the bracket 28. This gear 65 is normally in mesh with the gear 63, and is provided with a projection or finger 67 which is located within the cutout 59 of the lever 34. Thus upon oscillation of the lever 34, the shoulders 60 and 61 will alternately engage the projection 67 and thereby oscillate the gear 65 which in turn will oscillate the gear 63, the arm 62, the gear 27, and consequently the rock shaft 14. Thus the lever 34 in its forward direction of movement will release the pressure rolls 7 and 19, and in the opposite direction of movement will permit said rolls to return to their platen engaging position. The shoulders 60 and 61 are spaced apart a distance so that upon the rear movement of the lever 34 the shoulder 61 will not engage the projection 67 until after the latch 41 has been released from the line spacing mechanism and consequently the pressure rolls 7 and 19 will be released only after the completion of the line spacing operation.

Rolls 68 are rotatably mounted on a graduated rod 69 which is secured at its ends to the swinging bail arms 70. These rolls are also supported on the rod for independent adjustment therealong. The arms 70 are pivoted as at 71 to the end plates 5 of the carriage A. A coil spring 72 which is connected at one end to each bail arm 70 and at its other end to the end plate of the carriage, functions to yieldably retain the rolls 68 against the platen B. These rolls 68 are the means for holding the journal or book sheet C in position when the other two sets of feed rolls 7 and 19 are released for the insertion and removal of the invoices, thus permitting the retention of the book sheet in the line space position where the last entry was made sub-

sequent to the rotation of the platen and feed rolls preparatory to removing the invoices.

In operation the lever 24 is first moved forwardly to release the pressure rolls 7 and 19 from the platen. The journal or book sheet C is then inserted around the platen between the platen, and the separating plate 73 and the pressure rolls 7, 19 and 68. An invoice or billhead E and carbon sheet D are then inserted between the separating plate 73 and the table or support 74 and between the book sheet C and the pressure rolls 7, 19 and in front of the rolls 68. The lever 24 is then released by the operator and this lever together with the pressure rolls 7 and 19, then return to their initial positions. The desired entries are then printed on the invoice E and simultaneously on the record or book sheet C. The lever 34 is then moved rearwardly to first effect a line spacing operation to the book sheet C and to subsequently effect a release of the pressure rolls 7 and 19 during the continued rearward movement of said lever. The printed invoice E together with the carbon D are then removed, a new invoice and carbon are then inserted and the lever 34 moved forwardly to its initial position. This operation is repeated as often as desired and as a result the line spacing operation after each invoice is completed, the entries on the book sheet are spaced uniformly apart.

I claim:

1. In a typewriting machine, the combination with a platen, of a line spacing mechanism associated with said platen including a ratchet wheel fixed to the platen, an arm pivoted to swing about an axis concentric with the axis of the platen, a spring pressed dog mounted on said arm for cooperation with the ratchet wheel, an operating lever, a latch pivoted on the lever and normally connected to said arm, and a fixed abutment engageable by the latch to disconnect the latter from the arm upon a predetermined movement in one direction of the operating lever.

2. In a typewriting machine, the combination with a platen, of releasable pressure rolls cooperating therewith, a line spacing mechanism associated with said platen including a ratchet wheel fixed to the platen, an arm pivoted to swing about an axis concentric with the axis of the platen, a spring pressed dog mounted on said arm for cooperation with the ratchet wheel, an operating lever, a latch pivoted on the lever and normally connected to said arm, a fixed abutment engageable by the latch to disconnect the latter from the arm upon a predetermined movement in one direction of the operating lever, and means operative by the lever subsequent to the release of said latch for releasing said pressure rolls during movement of the lever in the same direction.

3. In a typewriting machine, the combination with a platen, of releasable pressure

rolls cooperating therewith, means for releasing said rolls including a cam shaft, and a gear fixed thereto and provided with an axially extending arm provided with a gear, and a line spacing mechanism for the platen including an operating lever fulcrumed coaxially with the platen and provided with a concentric cut-out portion forming spaced shoulders, and a gear rotatably mounted between the cut-out portion and the second gear and having driving engagement with said second gear, the rotary gear having a tooth projecting into the cut-out portion whereby upon movement of the operating lever in one direction the platen will be line spaced and the pressure rolls will be released.

4. In a typewriting machine, the combination with a platen, of releasable pressure rolls cooperating therewith, means for releasing said rolls including a cam shaft, and a gear fixed thereto and provided with an axially extending arm provided with a gear, and a line spacing mechanism for the platen including an operating lever fulcrumed coaxially with the platen and provided with a concentric cut-out portion forming spaced shoulders, and a gear rotatably mounted between the cut-out portion and the second gear and having driving engagement with said second gear, the rotary gear having a tooth projecting into the cut-out portion, a latch normally connecting the platen and lever for effecting a line spacing movement to the platen upon partial movement of the lever in one direction, and means cooperating with the latch to release the latter prior to the complete movement of the lever in said direction, the shoulders on the lever being spaced apart a distance sufficient to effect the line spacing operation prior to the release of the pressure rolls.

In testimony whereof, I have hereunto subscribed my name.

GEORGE F. HANDLEY.
